8 Claims. (Cl. 167—65)

This invention relates to a new derivative of gitoxin having valuable pharmacological properties. This invention also relates to pharmaceutical compositions having a cardiotonic activity and containing, as active ingredient, the new gitoxin derivative. This invention concerns also a process for preparing the new gitoxin derivative.

This new gitoxin derivative is pentaformylgitoxin of the following formula:

This compound ($C_{46}H_{64}O_{19}$) melts at 140–160° C., has a molecular weight of 921 and a saponification index of 6.51 (100 mg. of pentaformyl group correspond theoretically to 6.51 ml. of 0.1 N soda); the R_f of the compound is of 0.85 (in the chromatography field, R_f is the ratio of the distance between the spot of the product and the starting point to the distance between the starting point and the solvent front).

The pentaformylgitoxin according to this invention has an interesting cardiotonic activity, as shown by several pharmacological tests.

When the new derivative is included in the perfusion liquid of an isolated heart of a batrachian (such as a frog), a toning up followed by a heart failure in systole occur. The graphic recording of this phenomenon gives a characteristic curve of a cardiotonic substance.

The new compound has also been introduced in the circulatory system of mammals, such as cats and guinea pigs, and it has been found that said compound induces changes in the electrocardiogram. These changes are entirely typical of digitalic impregnation. It is known that digitalis purpurea contains cardiotonic glucosides similar to gitoxin and gitaloxin, the action of which is taken as a reference. These substances, when used in controlled amounts, make the heart movements regular, but they become noxious beyond a certain concentration. When the injection of the new derivative is continued, the excess of said derivative produces heart failure by ventricular fibrillation.

The lethal dose (LD_{50}) of the new compound has been determined on mice. This lethal dose amounts to 3.7 mg./kg. when the compound is orally administered, whereas the lethal dose is 3.5 mg./kg. when the compound is given by hypodermic injection. These values have been determined by the probit method on a sufficient number of animals (60 for each batch). These results show that the resorption is identical when the compound is given orally or parenterally.

For determining the minimum lethal dose on the guinea pig, the product has been slowly given by intra-

2

venous injection to six animals, using the Kneffel-Lenz method. A valve of 0.73 mg./kg. has been obtained for the pentaformylgitoxin, whereas the minimum lethal doses of gitaloxin and gitoxin is of 0.98 mg./kg. and 3.073 mg./kg. respectively. A comparison of these results shows clearly a higher activity of pentaformylgitoxin, due to a better solubility and diffusion ability than those of gitaloxin and especially gitoxin.

This invention relates to pharmaceutical compositions containing pentaformylgitoxin as active ingredient, as well as a pharmaceutically acceptable vehicle.

The new compositions may be administered orally under various dosage forms such as tablets, as well as parenterally and rectally.

For an initial treatment by means of tablets or pills, the daily dosage may be of 3 mg. of active ingredient. Each tablet may contain, for example, 0.2 mg. of active ingredient. After the initial treatment, a daily dosage

of 0.4 mg. of active ingredient may be given as sustaining treatment.

By injection, an initial dosage of 2 mg. of active ingredient may be sufficient, each vial containing, for example, 0.5 mg. of active ingredient dissolved in an organic solvent.

For the use of the product rectally, suppositories containing 0.5 mg. of pentaformylgitoxin are used.

This invention relates also to a process for preparing pentaformylgitoxin. According to the invention gitoxin is formylated in such a manner that the five hydroxy groups of gitoxin are formylated. In a particular embodiment of the process according to the invention, gitoxin is reacted with the mixed anhydride of formic acid and acetic acid, using an amount of anhydride at least equal to 170 times the stoichiometric amount of gitoxin. Preferably, an amount of anhydride of less than

390 times the stoichiometric amount of gitoxin is used. The reaction conditions depend from the amount of anhydride used and from the temperature of the reaction medium. The lower limit of the amount of anhydride is necessary for avoiding the formation of tetra-, tri- and di-formylgitoxin, whereas the higher limit of said amount is necessary for avoiding the production of anhydrogitoxin, the presence of which is shown by fluorescence in the ultra-violet spectrum. Moreover, by controlling the temperature so as to maintain this temperature at a value not higher than room temperature, the production of said undesired compounds is avoided.

The various gitoxin derivatives have been identified by upward chromatography on Schleicher Schull paper 2043b impregnated with formamide. The elution takes place with a mixture of cyclohexane and methyl ethyl ketone saturated with formamide. The following procedure is used:

To 100 ml. of 5:4 mixture of cyclohexane and methyl ethyl ketone, 20 ml. of formamide are added. The solution is stirred in a vial. Two phases are formed on standing. The upper phase is separated and used as eluent. A R_f of 0.84 ± 0.05 is found.

The fact that gitoxin has been completely formylated may be checked. In a mixture of acetic anhydride and pyridine, pentaformylgitoxin remains unchanged. This shows that the five hydroxy groups of gitoxin have been esterified. Moreover, a mild hydrolysis in acetone gives after chromatographic separation, gitaloxigenin and shows that the OH group in the 16-position has been formylated. The formyl groups have been identified by the Fauconnet process (Pharm. Acta. Helv. 34, 200, 1959). When pentaformylgitoxin is dissolved in a 9:1 mixture of tert-butanol and water saturated with lead acetate, a substantially complete conversion into gitoxin takes place after 18 hours.

The following examples are given for illustrating purposes.

EXAMPLE 1

10 grams of gitoxin are dissolved into 180 milliliters of anhydrous pyridine. The solution is cooled on a ice bath at 0° C.

The mixed anhydride of formic acid and acetic acid is prepared by dropping at 0° C. 205 milliliters of acetic anhydride into 308 ml. of formic acid. The solution is maintained at 0° C. during 4 hours. The mixed anhydride is then added slowly at 0° C. to the pyridine solution of gitoxin. When the addition is complete, the reaction mixture is maintained during 16 hours at room temperature. The reaction product is precipitated in 10 liters of ice cooled water. The precipitate is filtered off and washed with water. The residue is extracted with 150 ml. of chloroform and the chloroform extract is washed with water. The organic solution is then dried on anhydrous magnesium sulphate, concentrated to a volume of 50% of the initial volume and added, drop by drop, to 1 liter of cyclohexane at 0° C. The precipitate is filtered off and dried, so as to obtain 9.5 grams of pentaformylgitoxin (melting point: 140–160° C.; this melting point is difficult to measure, even after several precipitations). The following tables gives other characteristics of the obtained product, compared to the theoretical values.

Table I

	C	H	CHO groups	Molecular weight ¹	Saponification index ²
Theoretical values	59.98	7.00	15.75	921	6.51
Found values	60.39	7.12	15.74	951	6.34

¹ Determined by the Signer method.

² Number of ml. of NaOH corresponding to 100 mg. of pentaformylgitoxin.

Chromatographic tests have shown that the R_f is of 0.84 and that traces of tetraformylgitoxin ($R_f=0.45$) are contained in the product.

EXAMPLE 2

The method described in example 1 is used, except that 286 milliliters of acetic anhydride and 398 milliliters of formic acid are employed. When the reaction is complete, the mixture is treated with 1.5 liters of water.

Chromatographic tests show that the R_f is of 0.84 and that the obtained product is pure.

EXAMPLE 3

The method described in Example 1 is used, except that 326 milliliters of acetic anhydride and 490 ml. of formic acid are reacted. When the reaction is complete, the reaction mixture is treated with 20 liters of ice cool water.

Chromatographic tests show a $R_f=0.84$. The obtained pentaformylgitoxin is pure.

EXAMPLE 4

Tablets (weighing 100 milligrams) containing each 0.2 milligram of pentaformylgitoxin have been prepared with

5 a pharmaceutical excipient containing milk sugar, rice starch, potato starch, gum-acacia and talc.

EXAMPLE 5

10 Vials for injection containing 0.5 mg. of pentaformylgitoxin have been prepared. Each vial contains 0.5 milliliter of a 4:1 mixture of tertiary butanol and acetone.

When the injection has to be made, the content of the vial is diluted with 4.5 milliliters of physiological saline solution.

EXAMPLE 6

Suppositories weighing each about 2 grams have been prepared by mixing 0.5 mg. of pentaformylgitoxin to a known mass for suppositories.

What I claim is:

1. Pentaformylgitoxin.

2. A pharmaceutical composition in tablet form having a cardiotonic action and consisting essentially of pentaformylgitoxin, as active ingredient, and a tablet-forming carrier therefor, said tablet containing 0.2 milligram of the pentaformylgitoxin per 100 grams of tablet.

25 3. A pharmaceutical composition in the form of a unit dosage vial for injection, said vial consisting essentially of 0.5 mg. of pentaformylgitoxin in solution in 0.5 milliliter of a 4:1 mixture of tertiary butanol and acetone, said solution being diluted with 4.5 milliliters of physiological saline solution to yield a composition having cardiotonic action.

30 4. A pharmaceutical composition in suppository form having a cardiotonic action and consisting essentially of pentaformylgitoxin, as active ingredient, and a suppository-forming carrier therefor, said suppository containing 0.5 milligram of the pentaformylgitoxin per 2 grams of suppository.

35 5. A process for preparing pentaformylgitoxin, in which gitoxin is reacted with the mixed anhydride of formic acid and acetic acid until the five hydroxy groups of the gitoxin are esterified, using an amount of said anhydride of at least 170 times the stoichiometric amount of gitoxin.

40 6. A process for preparing pentaformylgitoxin, in which gitoxin is reacted with the mixed anhydride of formic acid and acetic acid until the five hydroxy groups of the gitoxin are esterified, using an amount of said anhydride comprised between 170 and 390 times the stoichiometric amount of gitoxin.

45 7. A process for preparing pentaformylgitoxin, in which gitoxin is reacted at a temperature at most equal to room temperature with the mixed anhydride of formic acid and acetic acid until the five hydroxy groups of the gitoxin are esterified, using an amount of said anhydride of at least 170 times the stoichiometric amount of gitoxin, the reactants being dissolved in pyridine.

50 8. A process for preparing pentaformylgitoxin, in which gitoxin is reacted at a temperature at most equal to room temperature with the mixed anhydride of formic acid and acetic acid until the five hydroxy groups of the gitoxin are esterified, using an amount of said anhydride comprised between 170 and 390 times the stoichiometric amount of gitoxin, the reactants being dissolved in pyridine.
